UNITED STATES PATENT OFFICE.

JOHN T. MELDRUM, OF TIPPECANOE, OHIO.

TRACK GAUGE AND LEVEL.

1,413,416.

Specification of Letters Patent. Patented Apr. 18, 1922.

Application filed December 6, 1919. Serial No. 342,948.

To all whom it may concern:

Be it known that I, JOHN T. MELDRUM, a citizen of the United States, residing at Tippecanoe, in the county of Harrison and State of Ohio, have invented certain new and useful Improvements in a Track Gauge and Level, of which the following is a specification.

This invention has for its object to provide a combined level and gauge for testing the elevation of the rails of a railway track to ensure proper spacing of the rails and to facilitate levelling and banking the rails for curved tracks.

Another object is the provision of a device of this character which is of exceptionally simple and inexpensive construction which is constructed almost entirely of pipe fittings and provides a rigid and durable structure capable of withstanding the rough usage to which devices of this character are ordinarily subjected.

With these and other objects in view as will appear as the description proceeds, the invention comprises the novel features of construction, combination and arrangement of parts which will be more fully described in the following specification and then finally pointed out with particularity in the claims hereunto appended.

Figure 1 represents a side elevation of the improved gauge and level.

Figure 2 represents an enlarged horizontal sectional view on the line 2—2 of Figure 1.

Figure 3 represents a fragmentary end elevation of the gauge, and,

Fig. 4 is an enlarged sectional detail taken on the line 4—4 of Fig. 3.

Referring to the drawing in detail, where in similar reference numerals designate corresponding parts throughout the several views the numeral 5 indicates the main or bottom bar of a frame structure composed of a plurality of relatively short pipe sections connected at intervals by the T-couplings 6. The end couplings 6 are connected with the centrally disposed members of terminal T-couplings 7 each of which is connected at its terminals with elbows 8 receiving relatively short pipe sections 9 supporting the angular track engaging members 10 which latter are preferably formed of strips of angle iron of adequate size to lend requisite strength and rigidity thereto in order that the parts will withstand the rough usage and abuse that devices of this character

are ordinarily subjected to. The vertically disposed portions of the end couplings 6 are connected with the vertical frame members 11 which are also preferably formed of sections and are connected by the couplings 13.

Elbows 12 are connected with the upper extremities of the end frame members 11 and connect with the terminals of the sectional top member 14 of the frame. The sections of the top frame member 14 are connected by T-couplings 15 the vertical portions of which are disposed in vertical alignment with the corresponding portions of certain of the T-couplings 6 and receive the parallel intermediate frame members 16, a coupling 17 being interposed between the two relatively short pipe sections disposed between the couplings 15.

A supporting plate 18 preferably formed of wood is provided with grooved terminals snugly receiving the parallel intermediate frame members 16 and the top and bottom edges of the supporting plate are firmly clamped between the flanges 19 of the T-couplings 6 and 15 whereby the plate is rigidly held in position.

A gauge glass 20 is set in the top horizontal edge of the plate 18 and the side portions of the plate adjacent the glass are preferably cut away to expose the glass tube to view.

A preferred type of gravity actuated indicating element 21 for indicating variations in the inclination of the frame structure, as when laying banked tracks at curves, is secured in a conveniently visible position upon the board or plate 18 adjacent the tube 20.

As will be understood, the vertically disposed portions of the angular track engaging members 10 are disposed in properly spaced relation to provide a gauge for setting the track rails at the proper distance apart and by reference to the tube 20 the operator is capable of quickly and conveniently determining when the rails are level with each other and, by reference to the gravity actuated indicator 21 the relative elevation of the track rails is indicated.

For convenience in the transportation of the track gauge and level over the rails of a railway track, rollers 10^a may be rotatably secured to the outer portions of the depending members of the angle irons or track engaging members 10 as suggested in Fig. 3,

but as these rollers are detrimental to accurate spacing of the rails they are removed when the track gauge is in actual use, which removal may be readily accomplished by unscrewing the winged nuts 10^b from the inner threaded ends of the spindle 10^c, on which the rollers 10^a are journaled, and withdrawing the latter from engagement with the openings formed in the depending portions 10 or flanges of the angle iron members 10. Due to the screw threaded connection between the several parts constituting the frame structure, the length of the latter may be readily varied, as desired, to secure accuracy 15 between the track engaging members 10 and to vary the space between the latter as may be found necessary in properly spacing the rails of tracks of varying gauges. The couplings connecting the sections and vertical 20 end members 11 of the frame structure permit convenient separation of these sections subsequently to which the sections of the bottom and top members 5 and 14 may be conveniently adjusted to secure the desired 25 variations in the length of the entire frame structure.

What I claim is:

1. A track gauge comprising an elongated skeleton frame structure, angular track engaging members carried by the frame structure, said frame structure consisting of longitudinal and transverse frame members and couplings therebetween, said frame members and couplings having screw threaded connections permitting the distance between the track engaging members to be varied, and an indicator clamped between said intermediate members.

2. A track gauge including an elongated skeleton frame structure consisting of superposed longitudinal members, end vertically extending and intermediate connecting members between the longitudinal members, angular track engaging members carried by the terminals of the lower longitudinal member, and an indicator supporting plate clamped between the intermediate connecting members.

In testimony whereof, I affix my signature hereto.

JOHN T. MELDRUM.
